(57) **CLAIM**

The ornamental design for a pizza storage container as shown and described.

DESCRIPTION

FIG. 1 is a perspective view of a pizza storage container showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a perspective view of the pizza storage container, shown in use with an exemplary lid; and,
FIG. 10 is a perspective view thereof, shown with the exemplary lid removed, and further shown in a folded state. The broken lines are shown for the purpose of illustrating environmental subject matter of an exemplary lid and form no part of the claimed design.

1 Claim, 10 Drawing Sheets
